S. GILTZ.

HYGIENIC CUSPIDOR.

APPLICATION FILED MAR. 30, 1920.

Patented Dec. 7, 1920.

Inventor
Solomon Giltz

By
William Clinton
Attorney

UNITED STATES PATENT OFFICE.

SOLOMON GITLITZ, OF MONTREAL, QUEBEC, CANADA.

HYGIENIC CUSPIDOR.

1,361,712.

Specification of Letters Patent.

Patented Dec. 7, 1920.

Application filed March 30, 1920. Serial No. 369,901.

To all whom it may concern:

Be it known that I, SOLOMON GITLITZ, a subject of the King of Great Britain, residing at Montreal, Province of Quebec, 5 Canada, have invented certain new and useful Improvements in Hygienic Cuspidors; and I do hereby declare that the following is a full, clear, and exact description of the invention, such as will enable others skilled 10 in the art to which it appertains to make and use the same.

The present invention relates to cuspidors and has for its object the provision of a device which offers most convenient and effective means for disclosing said cuspidor when use of same is required, and which may be advantageously utilized as an ornamental piece of furniture.

With the above and other objects in view 20 which will hereinafter appear as the description continues, the invention consists of the novel features of construction, combination and formation of parts as will be herein-after more fully described and particularly 25 pointed out in the appended claim.

In the accompanying drawings has been shown a simple and preferred form of the invention, it being, however, understood that no limitation is necessarily made to the precise structural details herein exhibited, but the right is hereby reserved to any changes, alterations or modifications to which recourse may be had that come within the scope of the claim without departing from 35 the spirit of the invention or sacrificing the efficiency of the same.

In the said drawings herewith submitted:

Figure 1 is a perspective view of the device as it stands when all communication or 40 course to the cuspidor therein inclosed is eliminated;

Fig. 2 is an end elevation in part section showing the interior of said device and more particularly the mechanism for operating 45 the lid covering the cuspidor;

Fig. 3 is an end elevation in full section showing the interior of the device as well as the position of said mechanism when the lid has been opened thereby;

Fig. 4 is a front elevation in section through line A—B of Fig. 3, with lid 50 opened; and,

Fig. 5 illustrates one form of the cuspidor which may be used and concealed within said 55 device.

Referring now more particularly to the ac-

companying drawings wherein like and corresponding parts are designated by similar reference characters throughout the several views:

The device embodying the present invention comprises a container or receptacle 1 of any convenient form supported on casters 2. A top portion 3 of said container, inseparable therefrom, provides for the adjusting of hinges 4, to which a lid 5 is pivotally connected. The top rigid portion 3 further provides for the adjusting therewith of a hollow post 6 within which a slightly inclined operating lever 7, slidably mounted within a sleeve 8, is pivotally disposed. The lower end 9 of said operating lever rests by gravity on another lever 10 fixedly connected to the pivoting lid 5, the hinges 4 serving as a fulcrum to said lever 10. This lever 75 10 has the extremity of its power arm formed with a laterally projecting portion 11, of which the interior profile, upon which rests the end 9 of the operating lever 7, is so configurated according to a curve, that it affords 80 constant and effective traveling contact for said end 9 of operating lever 7. Furthermore, said portion 11 of the lever 10 is so constructed and so taken care of in its dimensions and form that when the lid 5 is opened 85 and in vertical position, as shown in Fig. 3, the contact between the curved off end 9 of the operating lever and the extremity of the portion 11 is such that it is practically impossible to close the lid 5 without relieving 90 the operating lever from the operating position thus assumed, as clearly illustrated in Fig. 3.

A cuspidor 12, adapted for location within the container 1, may be removed therefrom, either through the top when the lid is open, or through the side 13; in this case, the vertical partition 13 is made to be removable or hinged on the bottom of the container or receptacle 1.

The germicide or disinfecting agents 15, in the accompanying drawings, shown adjusted to the lid 10, are otherwise adapted for location anywhere within the container 1. The lateral partitions forming said container are further provided with ventilating holes 16.

Operatively, the device herein described, being of ordinary hip height, or of any other required height, all that is required 110 when the use of the inclosed cuspidor is necessitated, is to apply with the hand, or

otherwise, a downward pressure on the extremity 17 of the operating lever 7. Immediately, responding to the pressure thus applied to the lever 10, the lid 5 will pivot 5 till it assumes the locked position illustrated in Fig. 3. After the cuspidor has been used, the said lid 5 is effectively closed by simply applying to the operating lever retaining the open position of the lid, a slight up- 10 ward pressure.

It will be noted in Fig. 3 of the drawing that the rounded end of the lever 9 engages the rounded end of the extension at the terminal thereof, when the lever 7 is in its 15 lowermost position. This obviously causes a binding engagement between the levers 7 and 10 and locks the cover in raised position, as shown in the drawing.

The present device embodying my invention 20 may be designed and constructed in form to suit the configuration and form of any cuspidor for which an artistic and sanitary concealment is required.

Having thus fully described my invention, what I claim as new and desire to secure by Letters Patent is:—

The combination with a cuspidor, of a container for receiving the latter, a pivoted closure for said container, a lever secured to the lower side of the closure and extending beyond the rear end thereof, said lever having an upwardly curved extension provided thereon, said extension having a rounded end, a vertically movable lever having a rounded end adapted to engage the curved portion of the extension and by downward pressure upon said lever raise the closure, said lever in its lowermost position engaging the rounded end of the extension and locking the closure in raised position, substantially as and for the purposes set forth.

In witness whereof I have hereunto set my hand.

SOLOMON GITLITZ.
